UNITED STATES PATENT OFFICE.

JOHN W. NESMITH, OF DENVER, COLORADO, ASSIGNOR TO ECONOMIC ASPHALT STREET REPAIRS COMPANY, OF DENVER, COLORADO.

APPARATUS FOR HEATING ASPHALT SURFACES.

SPECIFICATION forming part of Letters Patent No. 743,020, dated November 3, 1903.

Application filed December 27, 1902. Serial No. 136,836. (No model.)

To all whom it may concern:

Be it known that I, JOHN W. NESMITH, a citizen of the United States, residing at Denver, Colorado, have invented certain new and 5 useful Improvements in Apparatus for Heating Asphalt Surfaces, of which the following is a specification.

My invention is an apparatus designed to be used in the resurfacing or repair of asphalt pavements. As is well known, it is the practice to first soften the surface by applying heat thereto and then to cut out or remove the softened portion, adding fresh asphalt and treating this by rolling in the usual 15 manner. I have ascertained by practical tests that better results can be secured by applying heated gaseous products of combustion and air to the surface to be treated, and thus protecting the surface from the direct action of the flame.

In carrying out my invention, I have utilized the method disclosed in Letters Patent of the United States granted to me March 3, 1896, No. 555,731, and Patent No. 575,974, of 25 January 26, 1897. In these patents I disclose effective means for heating a blast of air, the air being passed through a chamber from a blower or like supply and being heated economically and effectually while passing 30 through the chamber to the point of use, the heating means employed being a suitable burner or burners supplied with oil or gas under a pressure greater than that of the blast to be heated.

35 My present invention is an economical and practical adaptation of the method referred to in an apparatus for the repair or resurfacing of asphalt pavements or, indeed, for use in any other situation requiring a highly-heated current or flow of gases discharging upon the surface to be treated.

My invention also includes means for modifying or regulating the temperature of the blast.

45 The apparatus disclosed includes many novel features of construction, as will be hereinafter more fully described.

In the drawings, Figure 1 shows one form of the apparatus mounted on the frame of a 50 steam-roller with the heating-chamber in section. Fig. 2 is an elevation of the apparatus

shown in Fig. 1. Fig. 3 is a sectional view of a modified form of heating-chamber with parts in elevation. Fig. 4 is an end elevation, partly in section, of Fig. 3. Fig. 5 is a section on line *x* *x* of Fig. 3. Fig. 6 is a section on line *y* *y* of Fig. 3. Fig. 7 is a plan, and Fig. 8 is an elevation, of another form of the apparatus.

Referring to Figs. 1 and 2, I find it convenient to mount the apparatus on the frame of a steam-roller or other suitable vehicle driven by power other than animal power, as ready approach is thus permitted to the place requiring repair without liability of tracking in the recently-repaired patches, though I may mount the apparatus in any suitable manner. A combustion-chamber is shown at A and is either water-jacketed or lined with asbestos. A blower B is mounted upon the chamber, and the blast is directed through the pipe C to a cross pipe or head D, supported on the end of the combustion-chamber, and from this head a series of air-delivery pipes *a* extend into the interior of the combustion-chamber for 75 preferably more than half the length of the chamber. These delivery-pipes may be provided in number as may be found suitable. I have shown six, but this number may be increased or diminished. The position of the 80 burner is shown at E, and this may be a burner adapted for oil, gas, or pulverized fuel, and is projected into the chamber A by any suitable means, such as air or steam under pressure. It is necessary, of course, as described 85 in my former patents, in order to maintain a flame in the chamber that the pressure back of the fuel shall be greater than the air-blast from the blower B. The fresh-air supply through the air-pipes *a* is thoroughly heated 90 in its passage, and this promotes the combustion of the fuel at the burner and throughout the combustion-chamber, and the gaseous products of combustion and air pass out through openings *b* in the front wall of the 95 combustion-chamber, these openings being preferably four in number, as shown in Fig. 2, though the number may be increased or diminished. A hood F, of any suitable form, is adjustably supported by chains *c* from projections *d*, mounted upon a shaft *e*, which is controlled by a lever *f*, and thus the hood may 100

be readily raised or lowered. The hood is of any shape, either, as shown, with a tapering top and side walls extending beyond the side lines of the apparatus at its extreme outer end, but 5 tapering inwardly to meet the side walls of the heating-chamber, or else of the form shown in Fig. 8, with the current of heated gases from the combustion-chamber entering it at the top, as more particularly hereinafter set forth. The hood may be provided with partition-walls g , and thus an independent heating-space is formed for one or more of the openings from the heating-chamber. The hood may thus be used simultaneously from 10 side to side by opening all the gates h controlling the exit-openings from the combustion-chamber, or where it is desired to operate on patches or small spots the heat may be confined to one or more of the spaces and the 15 gates of the other outlets kept closed. The gates are readily controlled by chains i , one for each gate, running over sheaves k , this being representative of any other method of operating the gates. My experience has 20 shown that this method of heating is so effective that the heat requires to be modified or else the asphalt street-surface will be destroyed by the intensity of the heat. I provide for this in one way by means of a valve 25 k' , located in a box l , intermediate the ends of the blower-pipe, with an opening controlled by this valve, as at n , leading into the top of the combustion-chamber. This valve serves 30 as a deflector and by proper adjustment may 35 deflect any desired proportion of cold air directly into the combustion-chamber, thus modifying the temperature of the gases being discharged.

In Figs. 3 to 6 I have shown a modified construction. In this form the combustion-chamber A' is shown as cylindrical with a suitable lining. The pipe for the blast is shown at C' discharging into a head D' , and from this head two pipes $E' E'$ communicate with a casing F' , 40 forming an intermediate chamber between the pipes E' and the combustion-chamber. A series of pipes G' , preferably four in number, though they may be more or less, form a constant means of communication between the 45 chamber F' and the interior of the chamber A' , these pipes being preferably of varying lengths, so as to distribute the heated combustion-air thoroughly, the burner being shown at E'' . In order to modify the heat 50 when this is found necessary or desirable, a valve H' is opened to a greater or less degree through the medium of a handle b' , with the result that a supply of cold air is admitted directly to the chamber A' , thus modifying 55 the heat of the outgoing blast of heated gases as it passes to the point of use through the exit-pipe G'' .

I do not limit myself to the details of construction, as it will be obvious that these may 60 be materially changed without departing from the spirit of my invention, the essence of which resides in utilizing the gaseous products of

combustion to soften or heat the surface to be treated without the direct action of the flame, and, secondly, in modifying or tempering the 70 intensity of the heat by the admission of a current of cold air. In this way the temperature is regulated and controlled so that it shall be above the melting-point but below the burning-point of the asphalt material 75 exposed to it.

Referring to Fig. 2, I may, as shown in dotted lines, subdivide the longitudinal compartments in the hood by dampers A^2 , so as to confine the heat when desired to smaller 80 areas. I may use one or more of these dampers in each division of the hood. I may also provide openings b^2 in the side and end walls of the hood, closed by shutters c^2 , so as to induce a current by allowing passage of the 85 heated gases, and thus more effectually heat the surface at that particular point. I may in case the heating-chamber is provided with a water-jacket utilize it for pumping the feed-water of the boiler through it. The jacket 90 may also serve the purpose of an ordinary boiler for the production of steam sufficient to operate the burner and blower.

In Figs. 7 and 8 I have shown another and most convenient form of construction and arrangement of the whole apparatus, operating in many of its various parts essentially as described above, but more conveniently arranged for service on the street. In this form of construction the machinery and appliances 95 are mounted on a frame conveniently made of channeled steel. A double-reversible vertical engine H has its crank-shaft provided with a pinion working in a gear on two counter-shafts placed below the engine. These 100 counter-shafts are supplied with two sprocket-pinions m , connected by sprocket-chains with sprocket-wheels p , attached to the driving-wheels, which carry most of the superincumbent load of the machine, and the machine is thus propelled on the street. A steering-wheel r is controlled by a hand-wheel t , operating-screw u , and nut v , which is pivoted to a controlling-arm j , said controlling-arm being keyed to the steering-head. A water-tank G may be provided as an auxiliary to the boiler. This tank is placed in the upper part of the combustion-chamber A , thus utilizing heat from said chamber. The main parts of the heating device are similar to those shown in Figs. 1 and 2. In Figs. 7 and 8 the air-blast pipe from the blower is inclosed within the casing of the heating-chamber, and from the head D^2 the pipes a^2 extend horizontally to near the rear wall of the chamber, the burner being shown at E^2 . Engine B^2 is utilized to actuate the blower. The outlet for the heated gases is through pipes $3 3$, which project from the front wall of the casing and have downward extensions 4. 110 Valves h^2 control the outflow of the gaseous products. The hood F^2 differs in construction, but not materially, from that in Figs. 1 and 2 in that it is dome-shaped and the gas- 115 120 125 130 135

eous products pass into it through the top through the pipes 4, which telescope in like extensions 5 from the hood. The hood is raised and lowered as in Figs. 1 and 2.

5 I claim—

1. In an asphalt-heater, a combustion-chamber, a blower or other source of air under pressure, one or more pipes between the blower and chamber, means for discharging air directly into the current of heated gaseous products of combustion, and means for regulating the quantity of such discharge of air into the heated gases, substantially as described.
- 15 2. In an asphalt-heater, a combustion-chamber, a blower, a chamber intermediate the blower and combustion-chamber, distributing-pipes leading therefrom to the combustion-chamber, a valved outlet from the combustion-chamber and a distributing-dome, substantially as described.

3. In an asphalt-heater, a combustion-chamber, means for introducing fuel therein under pressure, a blower, a pressure-pipe between the blower and chamber, an outlet for the heated gaseous products of combustion and a distributing-dome, substantially as described. 25

4. In an asphalt-heater, a combustion-chamber, means for introducing fuel therein under pressure and burning the same in suspension, a blower, a pressure-pipe for introducing air to the chamber to aid combustion and mix with the products thereof, an outlet for the heated gaseous products and a distributing-dome, substantially as described. 30 35

In testimony whereof I affix my signature in presence of two witnesses.

JOHN W. NESMITH.
